INVENTOR.

Franklin A. Smith Jr.

UNITED STATES PATENT OFFICE.

FRANKLIN A. SMITH, JR., OF PROVIDENCE, RHODE ISLAND.

BUTTON HOOK OR FASTENING.

SPECIFICATION forming part of Letters Patent No. 295,828, dated March 25, 1884.

Application filed January 14, 1884. (No model.)

To all whom it may concern:

Be it known that I, FRANKLIN A. SMITH, Jr., a citizen of the United States, residing at Providence, in the county of Providence and State of Rhode Island, have invented certain new and useful Improvements in Hooks or Fastenings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My present invention relates to that class of fasteners styled "hooks," for which an application is now pending in the United States Patent Office; and the object of my present invention is designed as an improvement on 20 the same. In the aforesaid application the hook is applied to the button by first cutting a slit or hole through the fabric, then passing the eye of a button through the hole, after which the hook is passed through the loop of 25 the button. The hook is then pulled up into the material until the head-bar lies closely against the under surface of the same. It will be seen that a hole the full width of the hook must be made in the fabric, and the button-loop alone prevents the hook from dropping 30 down. The hook is also liable to turn in the fabric, thus enlarging the hole.

35 My present invention has for its object to obviate these difficulties, and at the same time furnish a fastener which may be more readily attached to fabric.

To this end my invention consists of a hook or fastening cut from sheet metal, having a base-bar and hook integral therewith, said 40 hook having an upwardly-curved penetrating end, the base-bar and hook being substantially in the same plane with the metal in the finished hook, being in its normal or unbent condition as it existed in the sheet from which it 45 was cut, the whole being cut to form by suitable dies, all as will be more particularly described hereinafter in the following specification, and pointed out in the claims and drawings.

50 Referring to the drawings, Figure 1 represents a plan view of my improved fastener; Fig. 2, a view of the fastener passed through

fabric, with a button passed over it, ready for the final operation of bending; Fig. 3, a view of a button attached to fabric by means of my improved fastener; Fig. 4, a view of sheet metal, showing fastener cut therefrom ready for use.

Again referring to the drawings, A is a fastener, consisting of the base-bar *a*, from the cut edge of which extends a partial hook, *c*, terminating in an upwardly-curved penetrating end, *b*, the whole being in the same plane and cut from sheet stock, the metal of the finished fastener being in the normal or unbent condition in which it existed in the sheet out of which it was cut. The end *b* of the hook is made self-penetrating and curved upward, as shown in Fig. 1, to enable it to readily penetrate fabric, the fastener being cut to shape 70 substantially as shown in Figs 1 and 2 of the drawings.

In attaching a button to fabric by means of my improved fastener the end *b* is pushed through the fabric, making but a small hole, 75 until the base-bar lies closely against the under surface of the same. The button-loop is then passed on to the fastener until it lies within the hook portion *a'*, assuming the positions shown in Fig. 2. A pressure is now 80 brought to bear on the end of the fastener *b*. It is bent down into the upper surface of the fabric, clamping it firmly between the base-bar *a* and the end of the hook *b*, the portion of the hook from *a'*, Fig. 1, to the base-bar *a* 85 remaining unchanged as it was originally cut, the whole strength of the metal being thus retained at the point of strain, the greater part of the bending occurring at *a'*, or from that point of the hook to the end *b*. It will 90 be seen that a small hole is made through the material while the fabric is firmly clamped between the end of the hook and the base-bar; the end of the hook partially penetrating the fabric, thus preventing the fastener from becoming loose and dropping down, or from turning around, the button having free play in the hook, and at the same time not liable to become detached by use.

I am aware that it is not novel to strike out 95 a finished fastener from sheet metal in which the head and shank have a bearing edgewise of the metal.

Having described my invention, what I

claim, and desire to secure by Letters Patent, is—

1. A button-fastener consisting of a base or head bar from which extends a hook having an upwardly-curved penetrating end, the whole being cut from sheet metal, and being in its finished condition when so cut, substantially as shown, and for the purpose specified.

2. The herein-described button-fastener A,

consisting of the base-bar *a*, hook *c*, upward to curved end *b*, terminating in a penetrating end, substantially as shown and described.

In testimony whereof I affix my signature in presence of two witnesses.

FRANKLIN A. SMITH, JR.
